United States Patent Office

Des. 229,301
Patented Nov. 20, 1973

229,301

SHIPPING CARTON

Michael P. Patterson, 814 Old Settler's Trail, Apt. 4,
Hopkins, Minn. 55343

Filed July 21, 1971, Ser. No. 164,970

Term of patent 14 years

Int. Cl. D9—03

U.S. Cl. D9—225

FIG. 1

FIG. 2

FIG. 3

FIG. 1 is a perspective view of a shipping carton embodying my new design;

FIG. 2 is a top view thereof; and

FIG. 3 is a developed plan view thereof.

I claim:

The ornamental design for a shipping carton, substantially as shown.
